UNITED STATES PATENT OFFICE.

HOMER W. HODGE, OF ATLANTA, GEORGIA.

DESIGN FOR A BROOM-SHIELD.

SPECIFICATION forming part of Design No. 33,863, dated January 8, 1901.

Application filed December 15, 1900. Serial No. 40,054. Term of patent 14 years.

To all whom it may concern:

Be it known that I, HOMER W. HODGE, a citizen of the United States, and a resident of Atlanta, in the county of Fulton and State of Georgia, have invented and produced a new and original Design for a Broom-Shield, of which the following is a full, clear, and exact description.

Reference is to be had to the accompanying drawings, forming a part of this specification, in which similar characters of reference indicate corresponding parts in both the views.

Figure 1 is a perspective view of a broom-shield, showing my design; and Fig. 2 is a plan view of the same.

The design in its entirety consists of the shield-body A, approximately triangular in shape and terminating at the upper end in rearwardly-curved shoulder portions B B', formed near the middle, with rising segmen-

tal collar-sections C C' extending rearwardly beyond the common center of the sections, as plainly indicated in Fig. 2, the collar-sections appearing separated at the front of the shield.

The leading features of the design consist of the shield-body, the shoulder portions, and the collar-sections.

Having thus fully described my invention, I claim as new and desire to secure by Letters Patent—

The design for the broom-shield herein shown and described.

In testimony whereof I have signed my name to this specification in the presence of two subscribing witnesses.

HOMER W. HODGE.
